Attorney

UNITED STATES PATENT OFFICE

CLARENCE T. ROTTLER, OF SEATTLE, WASHINGTON

CYLINDER HONE

Application filed June 26, 1931. Serial No. 546,971.

My invention relates to cylinder honing tools, and has for its object to provide a hone which is convenient to use, easily set for any size of cylinder bore, within its range, in which the several hones can be adjusted, the hones of each pair simultaneously, independently of the other pair or pairs, and by like amounts, or in which all hones can be adjusted simultaneously and by like amounts, and further, a hone which by reason of this freedom of independent adjustment will enable the hones of one pair to be set at a slightly greater diameter than the hones of another pair, or vice versa, and maintained during further adjustment at the same difference of diameter, so that if two pair are used the coarse pair may be set out farther at first and the fine pair may be employed as guides, to prevent sticking and chattering, and finally in finishing the operation, the finer pair may be set out slightly in advance of the coarser pair and the latter will serve as guides.

It is also an object of my invention to provide a honing tool having the advantages enumerated, and others, which will be compact, simple in construction, and easy of adjustment.

My invention comprises the novel parts and the novel combination and arrangement thereof, as shown in the accompanying drawings, described in this specification and as will be more particularly pointed out by the claims which terminate the same.

In the accompanying drawings my invention is shown in a form which is at present preferred by me.

Figure 1 is a side elevation of my hone.

Figure 2 is a transverse section, substantially on the line 2—2 of Figure 1.

Figure 3 is an axial section, substantially on the line 3—3 of Figure 2.

Figure 4 is a transverse section on the line 4—4 of Figure 3, and Figure 5 is a longitudinal section, substantially on the line 5—5 of Figure 4.

By preference, there are employed two pairs of hones, generally designated by the numeral 3, which may be distinguished by suffixes, as 3a, 3b, 3c and 3d. These are arranged in pairs, 3a and 3b being the coarse pair, for instance, and 3c and 3d being the fine pair, although it will be understood, of course, that all might be of like texture; one pair might be non-abrasive in character, serving only as a guide. These are disposed parallel to each other, and parallel to the axis of a rotative base 1. This base is supported from a live shaft by any suitable means, such as the coupling collar 2, having part of a bayonet joint, indicated at 20, within its end bore 21, and supporting the base 1 by means of a connecting stub shaft 22, forming in effect an axial extension of the base 1, being threaded therein at 23. The coupling collar 2 is pinned to the shaft 22, as is indicated at 24.

The base 1 is provided with a longitudinal bore or bores 10 (see Figures 4 and 5), one for each pair of hones, and these bores preferably extend from end to end of the base. In them are received vertical shafts designated 4 and 40, to distinguish them. Tangent to these vertical bores 10 are transverse bores 11, in which are received sleeves 5. Various means may be employed to retain the sleeves 5 in place; for instance, their ends may be slightly shouldered (see Figure 3), and a collar 50 at one end holds the sleeve in place within its bore, the metal of the base being then swaged over to hold in place the collar 50. Thus supported, the sleeves may rotate each within its transverse bore 11.

There is a rotative engagement between each of the shafts 4 and the two sleeves with which it is associated, so that each vertical shaft 4 drives two sleeves 5, each sleeve controlling movement of diametrically opposite hones comprising a pair. To accomplish these ends, each sleeve may be formed with worm or skew gear teeth 54, and meshing 55

with these teeth are complementary teeth 45 upon the respective shafts 4. Internally, the sleeve is threaded and bolts 30 and 31 project inwardly from the respective hones 5 to engage within these threads in the sleeve, as may be seen in Figure 3. Preferably, and in order to give greater flexibility and a wider range of adjustment, one of the supporting bolts, as 31, is formed of greater diameter than the bolt 30, though both are alike in pitch, and the larger bolt 31 is axially bored or recessed in its inner end, as indicated at 32, whereby the inner end of the smaller bolt 30 may project within the recess 32.

Rotation of one of the shafts 4 will cause rotation of the two sleeves 5 with which its gears 45 are meshed. Rotation of these sleeves, one at the top and one at the bottom 20 of the base 1, will cause projection or retraction of the pair of diametrically opposite hones supported from these particular sleeves. The hones move inwardly or outwardly simultaneously, and by like amounts, 25 since the pitch of their supporting bolts 30 and 31 is alike. Rotation of the outer shaft, 40, will cause rotation of the sleeves 5 which are in mesh with this gear, and corresponding projection or retraction of the hones which 30 are supported from these sleeves, the hones being preferably arranged at ninety degrees to the first pair of hones.

Preferably, the two shafts 4 and 40 may be independently rotated, and to enable this 35 and to hold the shafts in place in the base, I provide a head 44 securable upon the upper end of each shaft above the base 1, and this head may be received between collars 25 and 26 upon the shaft 22, being held in place upon its shaft 4 or 40 by a pin 43 (see Figure 3). This head may be knurled, and thus the shaft to which it is connected may be rotated.

At times it is desirable to adjust all of the hones simultaneously and by like amounts, 45 and to enable this to be accomplished, I provide a pinion 46 or 47 upon the upper end of each shaft 4 and 40 respectively, and a third or driving pinion 6 is supported upon a collar 60, which is slidable axially of the shaft 22, so that it may engage both of the pinions 46 and 47, or may be disengaged from both of them. When engaged both shafts are turned simultaneously and in like amounts, maintaining throughout such adjustment any existing difference of setting, 55 and consequently all hones are projected or retracted simultaneously and equally. The collar 60 may be secured in operative or in inoperative position by the engagement of a spring-pressed follower 61 within one of two grooves 27 and 28 (see Figure 3) in the shaft 22.

The shape, size and precise manner of support of the hones is largely immaterial. As 65 herein shown, each is held in a channel 33,

one side of which is slightly inclined, and a wedge 34 is forced into place by a screw 35 to clamp the hone into its channel. Any suitable means to accomplish the purpose may be employed.

As is seen in Figure 4, the fine hones, 3c and 3d, are projected to the outer circle C, whereas the coarse hones, 3a and 3b, are projected only to the inner circle A. These circles may vary by only a few thousandths of an inch, but while the coarse hones, 3a and 3b, do not in such a situation wear down the cylinder bore, they are nevertheless effective, since any tendency to vibrate, to chatter, or to cause the axis of the honing tool 70 to depart from the axis of the cylinder bore 75 will cause the slightly retracted hones 3a and 3b to bear against the wall and to act as guides to steady the honing tool so that the hones 3c and 3d may continue to bear truly 80 and without chattering or undue noise.

The relative positions of the hones, may, of course, be varied, and it is to make such changes of relative positions possible that the independent adjustment of the pairs of hones is provided. However, when the hones have been set with the proper difference between their circles A and B, all may be projected or retracted at one time without changing this spacing between the circles. 85

Rotation is in the direction of the arrow B (Figure 4). To relieve the hones from too rigid a support, without departing from exact adjustment, the supporting bolts—for instance, the bolts 31—may be slit close to the hone, and at the rear side as the hone advances. Such a slit is indicated at 39. It permits the hone to yield slightly at its rear edge, yet sufficiently to cause it to bear always truly, and to operate without chattering, 100 in association with the complementary guide hones.

Such an arrangement enables all the work, coarse and fine, to be done with one honing tool, without removing and replacing it, and furthermore, it enables the hone to be adjusted to compensate for wear as it occurs, whereby the greater part of the stone can be used up, and it is never necessary to dress down the hone, nor is it necessary to reset 115 and dress special guide members. The hones themselves, that pair which are not at the moment working, will serve as guides for the pair which at the moment are working.

What I claim as my invention is:

1. In a cylinder honing device, in combination, a rotative base, hones supported from said base and disposed oppositely in pairs, and the pairs angularly disposed, and means to project and retract the hones of each pair equally and simultaneously, and independently of the other hones.

2. In a cylinder honing device, in combination, a rotative base, four hones supported from said base and disposed oppositely in

pairs of different texture, the pairs being set at 90° to each other about the axis of the base, and means to project and retract the hones of each pair equally and simultaneously, and independently of the other pair.

3. In a cylinder honing device, in combination, a rotative base, hones supported from said base and disposed oppositely in pairs, and the pairs angularly disposed, means to project and retract the hones of each pair equally and simultaneously, and independently of the other hones, and means selectively operable to project and retract all hones simultaneously and equally.

15 4. In a cylinder honing tool, in combination, a rotative base, four hones supported from said base and disposed oppositely in pairs, the pairs being set at 90° to each other about the axis of the base, means, including 20 a shaft for each pair disposed parallel to the axis of the base, for projecting and retracting the hones of each pair equally and simultaneously, and independently of the other pair, identical pinions upon each of 25 said shafts, and a drive pinion adapted to be engaged with both said first pinions, or to be disengaged therefrom, at will, and when engaged enabling simultaneous and equal projection and retraction of all hones.

30 5. In a cylinder honing tool, in combination, a rotative base, two shafts journaled in said base upon axes parallel to the axis of the base, rotative sleeves journaled transversely in said base, and disposed in two pairs, the axes of the sleeves in each pair being parallel, and at right angles to the axes of the sleeves of the other pair, driving engagement between the sleeves of each pair and its respective one of said shafts, 35 four hones disposed oppositely in pairs, parallel to the axis of the base, inwardly projecting supporting members at top and bottom of each hone, and receivable each within an end of a sleeve, and means operable upon 40 rotation of the sleeves to project or retract each supporting member, and the corresponding hone, equally and simultaneously at each end.

45 6. In a cylinder honing tool, in combination, a rotative base, two shafts journaled in said base upon axes parallel to the axis of the base, rotative sleeves journaled transversely in said base, and disposed in two pairs, the axes of the sleeves in each pair being parallel, and at right angles to the axes of the sleeves of the other pair, driving engagement between the sleeves of each pair and its respective one of said shafts, four hones disposed oppositely in pairs, parallel to the axis 55 of the base, inwardly projecting threaded supporting members at top and bottom of each hone, and the sleeve being threaded at each end to receive a thread support within each end, whereby upon rotation of a shaft 60 of the base, the corresponding sleeves are rotated and the

opposite hones supported therefrom are projected or retracted.

7. In a cylinder honing tool, in combination, a rotative base, two shafts journaled in said base upon axes parallel to the axis of the base, rotative sleeves journaled transversely in said base, and disposed in two pairs, the axes of the sleeves in each pair being parallel, and at right angles to the axes of the sleeves of the other pair, driving engagement between the sleeves of each pair and its respective one of said shafts, four hones disposed oppositely in pairs, parallel to the axis of the base, inwardly projecting supporting members at top and bottom of each hone, and receivable each within an end of a sleeve, and means operable upon rotation of the sleeves to project or retract each supporting member, and the corresponding hone, equally and simultaneously at each end, a pinion upon the upper end of each shaft, and a driving pinion selectively engageable with both said first pinions or with neither.

8. In a cylinder honing tool, in combination, a rotative base, two shafts journaled in said base upon axes parallel to the axis of the base, rotative sleeves journaled transversely in said base, and disposed in two pairs, the axes of the sleeves in each pair being parallel, and at right angles to the axes of the sleeves of the other pair, driving engagement between the sleeves of each pair and its respective one of said shafts, the ends of each sleeve being threaded, the opposite ends being of different diameter but like pitch, four hones disposed oppositely in pairs, parallel to the axis of the base, inwardly projecting supporting bolts at top and bottom of each hone, and threaded each within its corresponding end of a sleeve, the larger bolt being axially recessed at its inner end to receive the inner end of the opposite bolt, and means to rotate each shaft to project or retract the pairs of hones.

9. In a cylinder honing tool, the combination, a rotative base, longitudinally bored parallel to its axis, and having tangent transverse bores, a pair of diametrically opposite hones, means received in the transverse bores for supporting, projecting and retracting said hones, a vertical shaft received in the longitudinal bore, and operatively engaged with said means, a drive shaft extending axially of the base and having spaced collars thereon, and a head secured upon the end 115 of said vertical shaft and received between said collars to support the vertical shaft.

10. In a honing tool, in combination with a pair of diametrically opposite hones, means for supporting and rotating the same including posts extending inwardly from each hone, and said posts being slit in planes parallel to the axis of rotation, upon that side which is rearward as the hone rotates.

11. In a honing tool, in combination with

a pair of diametrically opposite hones, means for supporting and rotating the same including posts extending inwardly from each hone, and said posts being slit in planes parallel to the axis of rotation, upon that side which is rearward as the hone rotates, and guide members supported from and rotatable with the honing tool, and disposed intermediate the hones.

10. Signed at Seattle, King County, Washington, this 9th day of June, 1931.
